UNITED STATES PATENT OFFICE.

WILLIAM R. WARREN, OF NEW YORK, N. Y.

ROTARY KILN.

No. 839,053.

Specification of Letters Patent.

Patented Dec. 18, 1906.

Application filed January 19, 1906. Serial No. 296,889.

To all whom it may concern:

Be it known that I, WILLIAM R. WARREN, a citizen of the United States, residing at New York city, in the county and State of New York, have invented new and useful Improvements in Rotary Kilns, of which the following is a specification.

This invention relates to a kiln for burning cement and the like, and by means of this invention thorough conversion of material is assured.

This invention is set forth in the following specification and claims and illustrated in the annexed drawings, in which—

15 Figure 1 is a longitudinal sectional elevation of a kiln embodying this invention. Fig. 2 is a view of the discharge end and fuel-intake of the kiln. Fig. 3 is a section along xx , Fig. 1. Fig. 4 shows a cover.

20 The kiln can be of any diameter, usually about six feet, without being exact. This kiln a is shown with enlarged portion for some distance from its outlet or discharge-spout b . This spout is shown extending from an outer shield c , while the inner shield d is shown with outlet j in the center. The outer shield could, however, be omitted and the outlet attached directly to the shield d .

A fuel-intake is shown at e .

30 The shield c may have an outlet at the bottom with means for closing the same, so that material will collect in the kiln before discharging through spout b , which is located above the bottom or at the center portion of the kiln.

The enlarged part of the kiln embraces what may be called the "clinkering zone" of the device. If seen fit, the kiln can also have partitions.

40 The shield c may be supported in any manner desired.

By means of this invention the material to be converted into clinker will accumulate in the enlarged kiln-section or clinkering zone and be there retained long enough to be thoroughly converted into clinker. The outlet b being placed at an elevated point, as described, will prevent the material from passing off or going out except from the top of the accumulated mass.

The enlarged part or section needs to extend only substantially along the clinkering-zone, and being of increased diameter—for example, eight feet to a six-foot diameter kiln—will allow of thoroughly converting into clinker, as described, a much larger volume of material than is possible in the usual kiln.

Of course the relative dimensions given as example are not to be considered as limiting the scope of the invention.

A peep-hole may be in the discharge-spout around the intake-pipe or elsewhere, and the spout may have one or more dampers to more perfectly regulate the amount of air to the kiln.

I do not limit myself to the construction of an end shield or shields, as above set forth. The usual single shield resting upon the floor may be used and the end of the kiln be partly closed up by bricks or otherwise to retain the material, the clinker passing out over the part thus built up.

What I claim as my invention, and desire to secure by Letters Patent, is—

1. A rotary kiln having a double shield 75 with outlet and discharge-spout.

2. A rotary kiln having the lower portion closed against outlet and having a centrally located or elevated discharge for causing the material to accumulate and remain in the 80 kiln for a prolonged period to be thoroughly converted.

3. A rotary kiln having a discharge located away from the wall thereof and the lower portion closed against outlet so as to cause 85 the material under treatment to accumulate and pass off only from the top of the accumulated mass.

4. A rotary kiln having an enlarged portion with fuel-intake and an outlet located 90 above the bottom of the kiln, the lower portion of the kiln being closed against outlet.

In testimony whereof I have hereunto set my hand in the presence of two subscribing witnesses.

WILLIAM R. WARREN.
